SERVING SKILLET

James L. Siegmann, 108 E. Jefferson St.,
Goshen, Ind. 46526

Term of patent 14 years

Int. Cl. D7—99

U.S. Cl. D44—10

Fig. 1

Fig. 2

Fig. 3

FIG. 1 is a plan view of a serving skillet showing my new design in unassembled, laid-out position;

FIG. 2 is a perspective view in assembled position; and

FIG. 3 is a bottom plan view thereof.

I claim:

The ornamental design for a serving skillet, substantially as shown.
